UNITED STATES PATENT OFFICE

159,498

BRIC-A-BRAC WALL SHELF

Pius Luchetti, Corona, N. Y.

Application October 5, 1948, Serial No. 148,970

Term of patent 14 years

(Cl. D33—3)

To all whom it may concern:

Be it known that I, Pius Luchetti, a citizen of the United States, residing at 34-02 106th Street, Corona, county of Queens, New York, have invented a new, original, and ornamental Design for a Bric-a-brac Wall Shelf, of which the following is a specification, reference being had to the accompanying drawing, forming a part of such specification, and in which drawing:

Fig. 1 is perspective view of a bric-a-brac wall shelf, showing my new design.

Fig. 2 is a side elevation view thereof.

I claim:

The ornamental design for a bric-a-brac wall shelf, as shown.

PIUS LUCHETTI.
